UNITED STATES PATENT OFFICE.

PHILIP H. MARETT, OF PHILADELPHIA, PENNSYLVANIA.

KNEE SIGNAL.

Application filed July 13, 1920. Serial No. 395,926.

To all whom it may concern:

Be it known that I, PHILIP H. MARETT, a citizen of the United States, residing at Philadelphia, in the county of Philadelphia and State of Pennsylvania, have invented 5 certain new and useful Improvements in Knee Signals, of which the following is a specification.

The herein described device relates to attachments for automobiles and more particularly to devices adapted to be removably applied and attached to either the steering rod or column of automobiles or to other parts of the same for the purpose of sounding a horn or actuating some other signal without removing the hands from the steering wheel.

One of the objects of this invention is to provide a simple and practical attachment 20 which can be readily, easily and quickly attached to the steering rod or column or elsewhere on the car, if necessary, without alteration thereof, for the purpose of sounding a horn or other signal, in a quicker and 25 more convenient manner for the driver. A further object is to provide an attachment as herein described which will be inexpensive to manufacture, reliable in use, convenient in operation and of such nature as to 30 enable anyone to attach and use the same.

A further object is to provide a device capable of adjustment in order that it may be conveniently positioned with respect to the driver's knee and operated thereby.

While the foregoing explains the general 35 purpose and objects of the device, other objects and advantages will appear in the specifications that follow, in which the novel features, construction and arrangement of 40 the various parts will be brought out, described and claimed.

In the accompanying drawings, forming 45 a part of this specification, and in which corresponding parts are denoted by like designating numerals, is illustrated the preferred form of the embodiments of the invention capable of carrying the same into practical operation, it being understood that the invention is not necessarily limited thereto, as various changes in shape, proportions, and general assemblage of the several parts may be resorted to without departing from

the principle of the invention or sacrificing any of its advantages, in which:

Figure 1 is a view in perspective showing 55 the device ready for attachment.

Figure 2 is a view in perspective showing the casing for shaft operated by the pressure arm.

Figure 3 is a view in perspective showing 60 method of attaching the device to other parts of the automobile.

Figure 4 is a view in perspective showing device attached to the seat of automobile.

Figure 5 is a sectional view showing 65 push button operating means.

Figure 6 is a view in section showing portion of knee operated arm.

Figure 7 is a view in perspective showing 70 hollow shaft and pressure means.

Figure 8 is a view in perspective of means for operating signaling device.

Figure 9 is a view in perspective showing 75 arm for operating horn blown by exhaust or otherwise.

Coming to the precise details:—the arm 1 which is partially curved at a predetermined point and hollow at one end thereof 10, with the under portion of the hollow end cut out and shaped adapted to and fits 80 over an operating shaft 9 which is also curved, the outer end of the shaft is adapted to enter the hollow portion of the arm, with the cut away section 27 resting in position in the hollow portion and held therein 85 by the pressure of the spring member 11 which is removably secured in the hollow portion of the arm and presses against the shaped portion 12 of the shaft. What might be termed the operating end of the shaft 9 90 has secured thereon a substantially larger member 3 with the under side cut away to form the part 13 which is arranged and adapted to press against the spring contact 16, and either presses against a push button by the medium of the free end of the contact 14, or by electric contact as shown by the members 17 and 18. It is shown that the member 3 is to be enclosed in a casting 2 for the purpose of attaching the device to certain positions, the shaft 9 and the operating member 3 being adjustably secured therein by the threaded portion of

100 the shaft 9 as shown at 24 by simply turn-

ing the nut 25 or any securing means of like nature. In order that the casing 2 can be placed in any desired position, the shaped hollow member 4 is provided, which has a portion at its lower extremity cut away 8 to adjust itself to a steering rod of any shape, or a post or column, also to the shaped member 21, more particularly shown in Figure 3, which is attached to any portion of 10 the car as desired by the simple means of screws at the parts numbered 23. The adjustment is obtained by means of the pliable metal band 5 adjustably and removably attached to the shaped member by means of 15 the threaded member 6 inserted through the opening in the wing like portion 6'', a member, 7, heavier than the band receiving the threaded portion of the member 6 and permits of the adjustment of the band to a 20 larger or smaller circumference as desired by the openings 5'. When desired to use the device for other than push button or electrical control, the device is attached to any portion of the car to suit the convenience 25 of the driver by using the removably attached member as illustrated in Figure 3, attaching the operating portions thereto, and adjusting the arm to the required position, and using a "pull" of any 30 desired and well known material, such as wire, as shown by the numeral 26, attached

to the smaller end of the arm 23, the larger end removably attached to the threaded end 24 of the rod 9 being held there by the nut 25, and the pull leading to any desired signal. 35

I claim:—

A signal device, an arm hollowed at one end having the under side cut out and shaped, a spring member maintained therein, a shaped member removably and adjustably maintained in the said hollow portion and coming into contact with the aforementioned spring, said shaped member curved and having one end threaded, a relatively larger member between the curved portion and the threaded portion with the under side cut out adapted to come into contact with a push button or like means, the said relatively larger member removably maintained with a shaped member, the shaped member removably attached to a shaped member of a relatively different outline, and a supplemental attachment to a shaped member adjustably secured. 40 45 50 55

In testimony whereof I affix my signature in the presence of two witnesses.

PHILIP H. MARETT.
